JAMES D. REIFSNYDER, OF WEEHAWKEN, NEW JERSEY, AND GEORGE H. FATH, OF DENVER, COLORADO, ASSIGNORS TO STOKES & SMITH COMPANY, A CORPORATION OF PENNSYLVANIA.

APPARATUS FOR FEEDING AND GUMMING BLANKS.

1,403,635.

Specification of Letters Patent. Patented Jan. 17, 1922.

Continuation of application Serial No. 777,273, filed July 3, 1913. This application filed October 15, 1918. Serial No. 258,149.

To all whom it may concern:

Be it known that JAMES D. REIFSNYDER and GEORGE H. FATH, citizens of the United States, residing, respectively, at Weehawken and Denver, in the counties of Hudson and Denver and States of New Jersey and Colorado, have invented new and useful Improvements in Apparatus for Feeding and Gumming Blanks, of which the following is

10 a specification.

This invention relates to improvements in apparatus for feeding and gumming blanks, being a continuation of the application filed by us July 3, 1913, Serial No. 777,273.

15 One of the objects of the invention is to provide apparatus which will permit blanks and more specifically wrapper blanks to be fed individually from a stack to a predetermined point such as a wrapping station, each 20 blank being preferably provided with adhesive after leaving the stack and before reaching such point; in connection with this object the invention preferably provides the adhesive in the form of spots or zones.

25 Another object of the invention is the provision of means whereby the gumming instrumentality is normally maintained operative to apply the adhesive to the desired portions of the blank or wrapper present in 30 such instrumentality, with the instrumentality having its elements operating in a predetermined cycle, the means being operative to so affect the operating cycle as to prevent the production of conditions such as 35 would cause a succeeding blank to receive adhesive at an undesired point.

A still further object comprises the provision of wrapper blank feeding and gumming mechanism operative to deliver the 40 wrapper to a wrapping station, means being provided for supporting such wrapper at the said station under yielding tension for the purpose of folding it smoothly about a package fed in contact therewith.

45 Further objects are to provide apparatus for this purpose which is simple in construction and operation, durable in construction, and which can be manufactured at a relatively low cost.

50 To these and other ends, the nature of which will be readily understood as the invention is hereinafter disclosed, said inven-

tion consists in the improved construction and combination of parts, hereinafter fully described, illustrated in the accompanying 55 drawings, and more particularly pointed out in the appended claims.

In the accompanying drawings, in which similar reference characters indicate similar parts in each of the views,

60 Figure 1 is a view in side elevation of an apparatus embodying the present invention employed in connection with a packaging machine, parts of the latter being omitted.

Fig. 2 is an elevation of the structure of 65 Fig. 1 as seen from the blank-feed end of the machine.

Fig. 3 is a detail view of mechanism for elevating the stack of blanks.

Fig. 4 is an enlarged side elevation of 70 parts shown in Fig. 1.

Fig. 5 is a plan view of the same.

Fig. 6 is a sectional view taken on line 6—6 of Fig. 5.

Fig. 7 is a detail sectional view showing 75 the manner of lifting the uppermost blank from the pile or stack.

Fig. 8 is a similar view showing the manner of transferring the blank from the first 80 to the second feeding mechanism.

Fig. 9 is a detail view showing the application of adhesive to the blank.

Fig. 10 is a similar view showing the manner in which the blank is released at the close of the feeding operation.

85 For the purpose of illustrating the invention we have shown it as applied to a packaging machine in which the blanks being applied or gummed are adapted to be utilized in wrapping the package. Obviously, this 90 use is illustrative only.

Before entering into a detailed description of the mechanism forming the particular embodiment of the invention so illustrated, a brief description of the general operation 95 is given.

The blanks are carried by a table in the form of a stack, the table preferably being given such movements vertically as will tend to locate the uppermost blank on a proper 100 plane, especially at the time when the picker structure is made operative to select the blank.

The picker structure, in the embodiment

shown, is of the suction type, and is shown as mounted on a reciprocating carrier or carriage which serves to advance the selected blank. The picker is made operative 5 at the advance end of the blank—the edge of the blank which is in advance during the blank-advancing movement—to raise such end sufficiently to permit the introduction of a plate between the selected blank and 10 the stack, the plate being mounted on and movable with the carrier, being passed to a position to support the selected blank by the movements of the carrier in one direction. The carrier is also provided with gripping 15 means operative on the advance end of the blank, these latter becoming active on the selected blank as the carrier completes the movement which positions the selected blank on its plate support. Hence, when the 20 direction of movement of the carrier is reversed, the selected blank will be advanced with its advance edge gripped and with its body portion supported on the plate. This mechanism may be considered as a primary feeding mechanism.

The advance of the blank brings its advance edge into the space between gripping faces carried by an endless carrier which is adapted to travel only in the direction of 30 advance of the blank. This endless carrier is operated intermittently and preferably carries several separated or spaced gripping devices, these devices being normally closed. The travel cycle of the endless carrier is 35 so arranged as to provide a dwell in the movement when one of the devices is in position to receive the blank from the advancing carrier of the primary feeding means, the positioned gripping device being 40 open at this time to receive the blank, the device closing to grip the blank and the gripping faces of the primary means opening in advance of beginning the retreating movement of the primary means. The travel 45 of the endless carrier then advances the blank to the wrapping station, where the gripping device is temporarily opened to release the blank, and deposit it upon supports for resiliently holding the blank for 50 the subsequent wrapping operation.

At a suitable point in the travel of the blank from the stack to the point where it is released from the endless carrier, adhesive is applied to the particular face of 55 the blank. In the embodiment illustrated this adhesive application is made after the blank has been released from the gripping faces of the primary feeding means, the particular mechanism shown being adapted 60 to apply spots of adhesive to predetermined portions of the blank, being provided by a rotatable element which carries adhesive and with which a second element is adapted to co-operate, the latter being arranged to 65 normally form a face in opposition to the

adhesive-applying face, thus providing assurance of a proper adhesive application. In order, however, to prevent the second element from receiving the adhesive in case of failure to present a blank at the proper 70 time, a control mechanism is made active in such manner as to prevent the opposed faces of the two elements passing into direct contact, the result being that adhesive is not transferred to the second element, the faces 75 of the latter thus being prevented from being placed in a condition to produce undesirable application of adhesive to a succeeding blank.

In the drawings, 30 designates a base plate 80 that rests upon the floor and supports the machine. Bolted to the top of the base plate are two upright skeleton frames 31, 32, one on each side of the machine, connected together at their tops at the delivery 85 end of the machine by a horizontal bed-plate 33. An inverted U-shaped standard 34 is bolted to the bed plate 33 above the side frame 31, while opposite over the side frame 32 is a standard 35. Suitable cross-beams 90 are employed for producing a strong frame for the different mechanisms.

For the purpose of clearness, that part of the machine at the right in Fig. 1 may be considered as the front of the machine, 95 the direction of blank advance being toward the left in said figure—toward the rear of the machine.

Transversely of the machine above the base plate 30 is a horizontal driving shaft 100 37, mounted in suitable bearings carried by the base plate. On this shaft are secured the various cams and gear wheels by means of which the several parts of the machine are actuated. The shaft 37 rotates continuously during the operation of the machine and may be driven in the most convenient and suitable way. In the present instance the end of the shaft at the left of the machine carries a worm gear 39 turned by a 110 worm 40 on a short countershaft 41 also carrying a loose belt pulley 42 driven by some prime mover. A clutch 43 rotatable with but slidable on the shaft, connects the pulley 42 thereto when a hand lever 44 is 115 rocked.

Extending across the front of the machine between the side frames 31 and 32 and connected to said frames is a beam 45 through the center of which passes a bar 46 slidable 120 vertically therein and having on one side a rack 47 engaging a pinion 48 fast on a shaft 49 journaled in the side frames 31, 32, upon rotation of which shaft the rack bar is raised and lowered. A horizontal table 50 is carried on the top of the rackbar to support a stack of blanks A and moves with said bar. One or more guide pins 51 project downwardly from the bottom of the table 50 and slide through holes in the beam 45 to steady 125 130

the table and prevent it turning. Vertical fingers 52 project upwardly through slots 53 in one or both sides of the table against which the edges of the blanks A are placed and which serve to position said blanks laterally relatively to the folding mechanism. A single finger 54, pivoted on a bracket 55 on the under side of the table forms a stop for the front edges of the blanks and is adjustable. 10 The fingers 52 may also be adjustably secured to the frame of the machine if desired. A fixed finger 56 forms a stop and guide for the blanks at the advance edges of the latter. Shaft 49 projects through side frame 31 and has affixed thereon, outside the frame, a worm wheel 57 rotated by a worm 58 mounted on a shaft 59 supported in bearings 60 on said frame. A feather 61 secures the worm on the shaft and permits it to slide longitudinally for a limited distance. On one end 20 of the worm 58 is a grooved collar 62 with which pins 63 on a forked lever 64 engage, said lever being fastened on a short pivot pin 65 that extends through the side frame 31 and there provided with an arm 66 from the end of which a connecting rod 67 extends to a lever 68, pivoted to a fixed bearing at one end and engaging at its other end with a cam disk 69 on the driving shaft 37. At each 25 rotation of the driving shaft the cam disk 69 through the connections described, causes the arm 64 to rock and slide the worm longitudinally on its shaft a short distance. This movement of the worm turns the worm 35 wheel 57, its shaft 49 and the pinion 48 on said shaft a sufficient amount to raise the rack bar 46 and the wrapper table 50 carried thereby for a purpose to be hereinafter described. Upon passing of the cam surface 40 69^a of disk 69, the weight of table 50 and the blanks thereon will return the parts to their normal positions.

Over the table 50 is the blank feed carrier or carriage 70 comprising two vertically-arranged side plates 71 connected at their tops by a transverse plate 72. Legs 73, 74 depend from the bottom edges of the side plates and carry each two flanged rollers on the outer face, the rollers 75, 76 on each leg being 50 spaced apart in a vertical direction. Between the rollers 75, 76 on each side of the carriage is a horizontal rail 77 bolted to the respective side frames 31, 32 and separated a short distance therefrom by spacing collars 55 78. On these rails the carriage travels to and fro to feed the blanks. Fastened on the top of each side plate 71 of the blank carriage is a horizontally-disposed rack 79 with which engages a small gear wheel 80. These 60 gear wheels are mounted on a transverse shaft 81, rotatable in rearwardly-turned brackets 82 on the tops of the side frames 31, 32. A pinion 83 is fastened on the end of the shaft 81 projecting from the bracket 65 82 on the right side of the machine, with

which engages a toothed segment 84, pivoted at 85 to the side frame 31. From the segment 84 a rod 86 pivoted thereon extends downwardly and rearwardly toward the driving shaft 37 and is connected at its lower 70 end to a yoke 87, the legs of which straddle the driving shaft and are guided thereby. On one side of the yoke 87 is a roller 88 that enters a cam groove 89. The cam groove acting through the roller 88 as the shaft 75 revolves, moves the rod 86 longitudinally and rocks the toothed segment 84 which through the pinion 83 oscillates the shaft 81 and gear wheels 80 to advance and retract the carriage 70. 80

Projecting rearwardly from each side plate of the blank carriage 70 is a bracket 90 against the under side of which brackets are secured the ends of a thin horizontal plate 91 from the advance edge of which projects a plurality of tongues 92 while the rear edge extends at an angle from each end to the center forming a slightly projecting lip 93 that is given a downward curve or bend, the shape of which lip is clearly shown in Figs. 90 5, 6 and 7. Journaled in the ends of brackets 90 is a transverse rock shaft 94 on which are fixed a number of fingers 95 that extend toward the rear of the machine in a substantially-horizontal direction, their free ends 96 being bent downwardly and overlying tongues 92. Ends 96 are normally held in contact with the tongues by a spring 97 coiled around one end of the rock shaft and connected thereto and to one of the brackets 90. 100 An arm 98 projects in a forward direction from the opposite end of the rock shaft which on being depressed, lifts the fingers 95 from tongues 92.

Fastened on the top of the side frame 31 105 in rear of the shaft 81 are two bearings 100 on the innerside of each of which is pivoted a downwardly and rearwardly-inclined swinging arm 101, said arms lying parallel with each other and pivotally connected at 110 their free ends by a bar 102. Upon swinging the arms 101 the bar 102 moves in a vertical plane and when lowered lies in the path of arm 98 on rock shaft 94, or a roller on the end of said arm. At the proper time 115 in the feeding of the blank bar 102 is depressed, thereby rocking arm 98 and lifting the free end 96 of the fingers 95 for the purpose of releasing the blank.

For the purpose of swinging arms 101 and 120 raising and lowering bar 102, a lever 103 is connected to the pivot of one of said swinging arms 101 and projects rearwardly a short distance. From this lever a connecting link 104 extends downwardly to a 125 bell-crank lever 105 fulcrumed on the main frame and engaging at its free end with a cam 106 secured on the main driving shaft 37.

Extending transversely of carriage 70 at 130

- its rear end and journalled in the side plates 71 thereof is a shaft 107 on the left end of which is a pinion 108 that meshes with a horizontal rack 109 fastened to the top of the side frame 32. Secured to the shaft in the longitudinal center of the machine is a hollow roller 110 the chamber 111 therein communicating with the periphery of the roll at one point by a small hole 112 (Fig. 6.). Shaft 107 is made hollow for a portion of its length at least, and opens into chamber 111 in roller 110 from its right end upon which is a coupling 113 of suitable form connected by a flexible pipe 114 with a suction device of any suitable type for causing a current of air to flow continuously inwardly from the hole 112 in the roller 110, the purpose of which will be described hereinafter.
- 20 The blank feed carriage 70 does not deliver the blanks direct to the particular point of the machine where the wrapping operations take place, but carries them a part of the distance from table 50 to such point and then transfers them to a second feeding mechanism by means of which the distance is completed, the blanks being carried past an adhesive-applying device during this travel from the table. This second feeding mechanism will now be described.
- 25 Mounted to turn in the side frames 31, 32 in rear of the blank feeding carriage 70 are two horizontal shafts 115, 116, vertically disposed one above the other and at substantially equal distances above and below the plane of the blank feed plate 92. Secured on the upper shaft 115 is a gear wheel 117. A similar gear wheel 118 of equal diameter is secured on the lower shaft 116. These gear wheels intermesh so that the turning of one will necessitate the rotation of the other. Fastened on the upper shaft a short distance within the side frames 31, 32, are two sprocket gears 119 and 120 around which pass two sprocket chains 121. The chains 121 extend in a horizontal direction from said sprocket wheels to the extreme rear of the machine where they pass over smaller sprocket wheels 122 on a shaft 123 mounted in bearings 124 adjustable in upright brackets 125 bolted to the bed plate 33. From the sprocket wheels 122 the chains extend upwardly and forwardly to sprocket wheels 126 fixed on a shaft 127 mounted in bearings on the upper ends of brackets 128 rising from standards 34, 35. From sprockets 126 the chains pass downwardly to sprocket wheel 119, 120. The two sprocket chains carry gripping devices 129 that take the blanks from feed carriage 70 and transport them to the point where they pass into the operating instrumentalities of the machine.
- 30 Grippers 129, of which there are preferably several attached to the chains 121 and

spaced at equal distances apart, are each formed of two plates 130, each plate being connected to one of the chains, the plates in turn being connected by a transverse rod 131 the ends of which enter sockets in the plates 70 130 and are secured thereto by pins. A second rod 132 parallel to rod 131 extends between the plates 130 and is pivoted in sockets 133 formed on said plates. Fastened on rod 131 within the width of a blank A are 75 a number of gripping blocks 134 spaced apart, the under surfaces of which are flat as at 135 and from each of which surfaces at the rear depends a small hook-shaped lip 136. These blocks are secured to the rod 80 131 by set screws, thus permitting their adjustment on the rod to the width of the blank. Adjustably fastened on rod 132 are a number of fingers 138 that normally project toward the front of the machine when 85 in operative position and bear against the flat surface 135 of the block 134. These fingers 138 are also adjustable on rod 132 and are equal in number to blocks 134. The fingers are held normally in contact with 90 blocks 134 by means of a spiral spring 139 that surrounds one end of rod 132, said spring having one of its ends attached to the adjacent plate 130 and the other end to a collar 140 on rod 132. Fastened to the 95 other end of said rod 132 is a short arm 141 which may carry a roller 142 at its free end that at proper times engages a suitable cam 143 and a stop 152 and being depressed by said cam and stop swings the fingers 138 100 away from blocks 134 to receive and disengage at suitable intervals an edge of the blank.

Mounted to swing on shaft 115 close to sprocket wheel 119 is said cam 143 that extends downwardly into the path of arm 141 or the roller 142 thereon. A lug 144 projects upwardly from the cam above shaft 115 and is connected by a link 145 to a bell-crank lever 146 pivoted in a bracket 147 bolted 110 on the top of side frame 31. From lever 146 a connecting rod 148 extends downwardly toward main driving shaft 37 and is there pivoted to one arm of a bell-crank lever 149, the other arm of which—or a roller 115 thereon—bears against a cam disk 150 on driving shaft 37. On cam disk 150 is a cam surface 151 that at the proper time rocks bell-crank lever 149 and through the connecting rod 148, bell-crank lever 146 and 120 link 145, rocks cam 143 to depress arm 141 and swing the fingers 138 away from blocks 134.

Before proceeding further a short description of the operation of the blank feed 125 carriage 70 in picking up and carrying a blank to the secondary carrier and the manner of transferring the blank to said carrier will be given.

The vertically-movable table 50 carrying a 130

stack of blanks A is elevated in the manner hereinafter described until the uppermost blank contacts with the under surface of the suction roll 110. At the beginning or during 5 the movement of the feed carriage 70 toward the front of the machine, suction roll 110, moving therewith, is rotated by pinion 108 engaging rack 109. The parts are so timed that hole or perforation 112 in the 10 suction roll will be on the under side of the roll when the latter arrives adjacent the advance end of the wrapper or blank, as shown in Fig. 7. The suction through said roll will hold this edge of the blank against 15 the roll and as the carriage starts or continues its travel in this direction, the reverse rotation of the suction roll—clockwise in Fig. 7—will lift the advance edge of the blank above the stack, as shown in said figure, and 20 permit the downwardly-inclined lip 93 of plate 91—which also reciprocates with the carriage—to pass below the uppermost blank or between it and the balance of the stack. Finger 54 at the front edge of the stack 25 holds the selected blank against forward movement so that upon completion of this movement of the carriage, the selected blank A will overlie plate 91, the advance edge of the blank being supported by tongues 92 30 beneath the free ends 96 of fingers 95, the latter being elevated to permit the blank to pass thereunder.

The carriage 70 then reverses its movement to the direction of blank advance, 35 whereupon the swinging arms 101 are actuated by cam 106 to raise bar 102 so that fingers 95 by the force of spring 97 are caused to clamp the blank between their forward ends and tongues 92. The carriage 40 continues this advance movement toward the secondary feeding mechanism which in the meantime has brought one of the gripping devices 129 into position to receive the blank from the carriage. The gripping device at 45 this time is stationary and as the carriage, advancing thereto, reaches the limit of its movement, tongues 92 and fingers 95 enter between the blocks 134 of the gripping device. Fingers 138 of this device are, at this 50 moment, in their downward position or away from blocks 134 so that the advance edge of the blank is carried beneath said blocks and above the hook-shaped lips 136 (Fig. 10). Cam 143 now releases arm 141 so that 55 spring 139, turning rock shaft 132, swings fingers 138 up against the under side of the blank and clamps it against the flat surface 135 of blocks 134. At the same time bar 102 is depressed and lifts fingers 95 of the 60 blank feed carriage 70 to release the blank from plate 91. The secondary carrier with its gripping device 129 now advances while the feed carriage 70 begins its travel toward the front of the machine and begins its 65 cycle of operation on the succeeding blank,

the suction roll picking up the top blank to permit the plate 91 to pass thereunder as heretofore pointed out.

To enable plate 91 to pass freely between the top or selected wrapper blank and the 70 stack of blanks, table 50 is lowered a short distance during each cycle to relieve the pressure of the blanks against the suction roll by cam 69 actuating, through suitable connections heretofore described, arm 64 to 75 slide worm 58 on its shaft and give a short turn to worm wheel 57, its shaft 49 and pinion 48 in engagement with rack 47. After plate 91 has passed beneath the wrapper blank and separated it from the stack, 80 table 50 is again elevated. This rising and falling movement of the table is designed only to relieve the pressure on the suction roll and not to feed the table and stack gradually upward as the blanks are successively removed from the top of the stack. Other means are employed for this gradual feed of the table, which means will now be described.

The toothed segment 84 (Fig. 2), from 90 which motion is imparted to reciprocate the blank feed carriage, has projecting forward from its hub an arm 153 connected at its end by a link 154 with a lever 155 pivoted to swing freely on the short shaft 59 at the 95 right hand side of the machine. Fixed on said shaft at one side of lever 155 is a ratchet wheel 156 with which a pawl 157 pivoted on lever 155 engages. At each operation of the machine to feed the blank the oscillation of 100 the toothed segment 84 swings arm 153 which through the connections described actuates the arm 155 in such manner that pawl 157 carried thereby will turn ratchet wheel 156 and shaft 59 a short distance. This partial 105 rotation of shaft 59 and worm 58 keyed thereon will in turn impart a slight movement to worm wheel 57, a movement sufficient however to elevate the table 50 a distance to compensate for the blank previously 110 removed. It will thus be apparent that every time a blank is removed from the stack table 50 supporting the stack is elevated a very little but sufficient to maintain the top of the stack at a point where the top blank 115 will be located at a substantially constant plane relative to the plane of the suction roll. If from any cause the top of the stack is elevated higher than its normal position, pawl 157 is disengaged from ratchet wheel 120 156 by trip mechanism comprising a disk 158 lying close to one side of ratchet wheel 156 and having a notch 159 in its periphery which normally is opposite pawl 157 and permits the latter to engage the ratchet 125 wheel, the pawl itself being sufficiently wide to project beyond said ratchet wheel and over the edge of the disk. Disk 158 turns freely on shaft 59 and pivotally connected to said disk is a rod 160, the upper end of which is 130

attached to a lever 161 fulcrumed on a bracket projecting from the main frame. A link 162 extends from lever 161 to one end of a second lever 163 pivoted at 164 to the main frame and provided on its other end with a shoe 165 that bears upon the top of the stack of blanks. When the stack of blanks is raised to the proper height, as in Fig. 3, the parts just described are in the position shown in said Fig., but should the table 50 and blanks be raised above normal even a slight distance, shoe 165 will move with the blanks and this movement, transmitted through levers 163 and 161 and their connections, will turn disk 158 in the direction indicated by the arrow sufficiently far as to swing pawl 157 away from the ratchet wheel 156 and hold it out of engagement therewith until the stack has been lowered to the proper position. During the time disk 158 is in engagement with pawl 157 the swinging movement of arm 155 will not, as is evident, cause the actuation of ratchet wheel 156 and through said ratchet wheel the gradual feeding upwardly of table 50. Table 50 is raised and lowered manually whenever desired by placing a crank (not shown) on the projecting end 166 of shaft 59, said end having a polygonal outline as shown to receive the crank. By disengaging pawl 157 from the ratchet wheel the shaft may be turned in either direction to cause the raising or lowering of table 50.

The second feeding mechanism is preferably in the form of an endless conveyor including the chains 121 and the gripping devices 129 are moved intermittently the distance between two of these devices at each operation of the machine. This intermittent advancing movement is imparted to said second feeding mechanism by a cam 167 fast on main driving shaft 37 rocking a lever 168 pivoted to side frame 32 near base plate 30 and having a segmental rack 169 on its upper end that meshes with a gear wheel 170 mounted to turn freely around a stub shaft projecting from side frame 32. Affixed to gear wheel 170 and turning on the same stub shaft is a larger gear wheel 171 that meshes with a gear wheel 172 which turns loosely on shaft 116. Gear wheel 172 is of less diameter than gear 171 and has fastened to its outer side a disk 173 in which is formed a concentric depression 174 on its exterior face. Rotating within said depression is a circular plate 175 fixed on shaft 116 and having a notch 176 in its edge with which notch engages a dog 177 pivotally mounted in an offset 178 from depression 174. The gear wheels are so proportioned that at each vibration of lever 168 the segmental rack 169 thereon turns gear wheel 170 first in one direction and then in the other. This same movement through gear wheel 171 being imparted to the smaller gear wheel 172 turning

freely on shaft 116, the latter gear wheel and its disk 173 make a complete revolution in each direction. When the toothed segment 169 is moved toward the rear of the machine, disk 173 moving in the direction of the arrow, will, through dog 177 engaging the notch 176 in plate 175, turn the plate and shaft 116 in the same direction. The return movement of segment 169 rotates disk 173 in the opposite direction, but dog 177, swinging within its offset 178, is released from plate 175 and returns to its first position while the plate and shaft 116 remain stationary. Shaft 116, by means of gearing 118, 117, turns shaft 115 through a complete revolution and thus advances the second feeding mechanism the required distance.

As heretofore pointed out, the apparatus is preferably designed to apply an adhesive to one face of the blank. For instance, if the blank is being employed for the wrapping of a package, the adhesive will permit of securing the folds of the wrapper in position relatively to each other or to the package contents. In the present embodiment of the invention, this adhesive is applied to the upper face of the blank as it lies extended on the table and passes along in the plane of the feeding movement, the particular point in the travel of the blank from table 50 utilized in this particular embodiment being just after the blank has been gripped by the secondary feeding mechanism, thus locating the blank at a convenient point in the specific arrangement of feeding mechanisms shown.

The particular adhesive-applying means shown (Fig. 6)—a form designed for spot or zone application and illustrating the more difficult phases of adhesive application—comprises two arms 179 adjustably secured on shaft 115, each arm 179 having a jaw 180 on its outer end and within which is clamped a short curved pad 181. These arms are made adjustable so that they may locate the pads 181 at predetermined points of the blank, these pads being designed to apply the adhesive adjacent the lateral edges of the blank. Affixed to shaft 115, between the arms 179, is a plate 182 that extends in a radial direction, the outer edge of said plate having a jaw 183 within which is clamped a straight or lineal paste-applying pad 184, the length of which extends transversely of the machine while the jaws which hold it are substantially the same length as the width of the blank. Plate 182 and radial arms 179 stand at such an angle one to the other that as shaft 115 rotates, pads 181 will apply the adhesive at each of the side edges of the blank at about the center of its length while pad 184 will apply adhesive along the entire length of the rear end of the blank—the end which last passes beneath the adhesive applying device. Arms 185 and a plate 186, each carrying pads similar to 180

those on arms 179 and plate 182, are mounted on shaft 116 and extend radially from such shaft at such angles that as the shafts 115, 116, rotate pads 187 on arms 185 will 5 form abutting surfaces for pads 181 as they contact with the blank, and pad 186 serves the same purpose for the pad 184, the blank extending between the opposing faces of the several sets of pads.

10 The adhesive material is carried in liquid form in a trough 189 that extends transversely across the machine and is supported by extensions 190 from the side frames 31, 32, in rear of shaft 115. Rotatably mounted 15 in bearings fixed to said extensions is an adhesive-collecting roller 191 that dips into the adhesive contained in the trough and picks up the same as it rotates, the excess adhesive being removed from the roller by a 20 scraper 192 in the form of a spring plate, one end of which bears on roller 191 with greater or lesser pressure as permitted by the regulation of adjusting screws 193. The applying roller 194 runs in contact with 25 roller 191 and takes adhesive therefrom and transfers it to pads 181 and 184 as the latter are carried in the circular path. A belt pulley 195 loose on the shaft of roller 191 and driven from any suitable source of 30 power turns said shaft when connected thereto by a clutch 196. The applying roller 194 is driven positively from the gathering or collecting roller 191 by intermeshing gear wheels 197, 198 on the shafts of said rollers.

35 Pads 181 lie at the same distance from the axis of shaft 115, as the chains 121, so that the pads move at the same speed as the blank which is being carried by the chains. The co-operating pads 187 also move at the same 40 speed so that when the two pads 181 and 187 come together, as indicated in Fig. 9, but separated by the blank A, they move with the blank and at the same speed as the blank.

45 It may sometimes happen that a blank fails to enter between the tongues 92 of plate 91 and fingers 95 above said plate, and therefore when the carriage 70 moves toward the second feeding mechanism it does so 50 without carrying a blank to the gripping device 129. If such be the case, when shafts 115 and 116 rotate the pads 181 and 184 carried thereby would contact with pads 187 and 188 and cover the same with adhesive, 55 there being no blank between them. This would, of course, cause great trouble at the next operation when a wrapper blank is fed. To prevent such an occurrence means are provided to prevent the rotation of 60 shafts 115 and 116 when a blank fails to be fed to the second mechanism.

This means comprises a rocking lever 199 (Fig. 4) pivoted on plate 175 that is secured on the outer end of shaft 116. One 65 arm of this lever is in contact with the free

end of dog 177 and when moved will swing said dog out of notch 176 in said plate, but is normally prevented from doing so by a spring 200. Upon the other arm of the lever 199 rests a finger 201 projecting 70 from a sleeve 202 pivoted on side frame 32. A second finger 203 extends in the opposite direction from sleeve 202 and is provided with a projecting pin 204 on its outer end. This pin 204 enters an L-shaped slot in a 75 vertical bar 205 pivoted on one end of a rocking lever 206 connected at its other end by a link 207 to an angular plate 208 mounted to swing on a pivot 209 and lying in the path of a cam bar 210 carried by carriage 70. The L-shaped slot within which pin 204 lies has a horizontal leg 211 normally in line with said pin and a downwardly-extending vertical leg 212 also in line with said pin. When the carriage 80 travels toward the second feeding mechanism to carry the blank thereto cam plate 210 strikes swinging plate 208 and through the several connections raises bar 205, but because of leg 212 of the L-shaped slot being 85 in line with pin 204, fingers 201, 203 will remain quiet and at the proper time shafts 115, 116 will rotate under the normal operations, but should there be no blank on carriage 70, bar 205 will be drawn downwardly by means hereinafter described and leg 211 of the L-shaped notch will engage pin 204 and as plate 208 is depressed and bar 205 elevated, fingers 201, 203 will be 90 rocked and lever 199 swung to disengage 95 dog 177 from notch 176 in the plate so that rotation of disk 173 will take place without carrying plate 175 with it and consequently shafts 115 and 116 will not turn.

The means for swinging bar 205 so that 100 leg 211 of the L-shaped notch can engage pin 204 comprises an electro-magnet 213 mounted on side frame 32 in position to attract bar 205 or an armature thereon, said electro-magnet being in circuit with a battery from which wires extend to plate 91 and to an insulated stop 214 on the depressed end 96 of one or more of the fingers 95. When a blank A is between tongues 92 and fingers 95, said blank serves as an insulation and the electro-magnet is not energized, but should carriage 70 advance without a blank the insulated contact, touching tongue 92, would close the circuit through the electro-magnet 213 and attract bar 205, 110 causing leg 211 of the L-shaped slot to engage pin 204 on arm 203.

115 As will be understood the blank is retained within the grip of the gripping device 129 during the operation of the gumming instrumentality, so that the gummed blank will be advanced flatwise in its own plane until stop 152 is reached, thus bringing into operation the releasing action by 120 opening the gripping device. This position 125 130

is shown in Fig. 10 as located to deposit the gummed blank over the folding well of the wrapping station of the machine.

As is usual in the packaging or wrapping art, a package is fed into contact with the wrapper positioned over the folding well of the machine, the wrapper being folded about the package as both move into the folding well. For the purpose of folding the wrapper smoothly about the package when the latter is fed into contact with the former, I provide means for supporting the blank A at the wrapping station under yielding tension, the wrapper being by this means drawn tightly about the package as both are fed into the folding well of the machine. To this end the wrapper, upon the releasing action of the gripper device, is, as pointed out above, deposited over the folding well of the machine and on a front supporting table 216 and a rear supporting table 217, (see Figure 10) folding well 215 being defined by the space between the said tables 216 and 217; these tables being mounted above the bed plate 33. The inner edges of these tables, which overhang the opening or well 215, are each provided with a resilient roller 221. Extending across each table a short distance back from the rollers 221 is a passage 227, from which passage small holes 228 are made to the upper surface of the two tables, said passages 227 being connected by pipes (not shown) with a suitable suction device. In the present instance each passage 227 is formed in a bar 230, formed in a groove extending across the respective tables 216 and 217. As will be apparent, when a package located above the tables is moved into contact with the wrapper A, drawing the same off the supporting tables and both package and wrapper moving into the folding well 215, the wrapper is drawn tightly about the package as it passes between the rollers, owing to the fact that the movement of the ends of the wrapper is retarded by the suction and small holes 228 leading thereunto from the top of the tables and which are covered by the wrapper. The suction tends to draw the wrapper against the tables and holds them in this position; but the downward movement of the package exerting a greater force than is exerted by the suction, the ends of the wrapper are gradually drawn across the holes 228, the suction through them, however, being sufficient to hold the wrapper under such tension as to draw it tightly about the package, effecting a securely folding function.

In the operation of the present invention, the blank supporting table 50 is lowered and a stack of blanks A placed thereon between the side fingers 52, the finger 54 and finger 56, these latter fingers being located at the front and rear of the stack, thus alining the

stack. The table is then raised into operative position with the uppermost blank against suction roller 110 and shoe 165 of the tripping mechanism, by manual rotation of shaft 59. The trough 189 is filled with liquid adhesive and the machine operated sufficiently before feeding blanks as to thoroughly coat rollers 191, 194 and applying pads 181, 184 with the adhesive. The machine being now ready for operation, power is applied to main driving shaft 37 by actuating the shifting lever 44. At the proper time carriage 70 with the suction roller 110 advances over the stack of blanks, roller 110 picking up the advance edge of the uppermost blank at the end of such movement to enable plate 91 to pass between said blank and the stack, during the movement of the carriage in the opposite direction. At the conclusion of such latter movement of the carriage, the selected blank is clamped between tongues 92 of plate 91 and the pivoted fingers 95, and is advanced by the carriage at the next feeding movement thereof to deliver the advance edge of the blank to grippers 129 on chains 121 that at the conclusion of the feed movement of the carriage transports the blank to its position over the folding well, depositing the same on the resilient supporting tables for resiliently holding the wrapper ends by pneumatic means against the wrapper withdrawal activity for the folding operation to effect the securely folding function described in detail above. During the travel the blank passes the adhesive applying mechanism and receives the adhesive on its upper face. Should the primary feeding mechanism fail to properly position the blank on the plate 91, the trip mechanism described is made active through the completion of the circuit between finger 96 and tongues 92—these acting on the order of a detecting mechanism—thus setting in motion the structure which prevents the adhesive applying mechanism from bringing the opposing sets of pads into physical contact, the feeding mechanisms simply continuing their regular cycles of operation, so that stopping of the machine is unnecessary to take care of the failure of blank feed.

As heretofore indicated, the particular construction shown is more or less illustrative. It will be readily understood that changes and modifications therein may be found desirable or essential in meeting the various exigencies of use, and we desire to be understood as reserving the right to make such changes as may be found necessary or desirable in carrying out the broad principles of the invention in so far as the same may fall within the spirit and scope of the invention as expressed in the accompanying claims when broadly construed.

What we claim is:

1. In mechanism for selecting, gumming and delivering blanks individually and successively from a stack of blanks to a predetermined point, primary feeding means for selecting and advancing a blank from the stack, secondary feeding means for receiving the selected blank and delivering it at such point, said secondary feeding means including an intermittently-movable endless carrier and spaced normally-closed gripping devices mounted thereon and adapted to be opened to receive and discharge the selected blank, and means for applying adhesive to the blank while enroute to said point.

2. In mechanism for selecting, gumming and delivering blanks individually and successively from a stack of blanks to a predetermined point, primary feeding means for selecting and advancing a blank from the stack, secondary feeding means for receiving the selected blank and delivering it at such point, said secondary feeding means including an intermittently-movable endless carrier and spaced normally-closed gripping devices mounted thereon and adapted to be opened to receive and discharge the selected blank, and means for applying adhesive to said blank while the latter is held by the gripping devices.

3. In mechanism for selecting, gumming and delivering blanks individually and successively from a stack of blanks to a predetermined point, primary feeding means for selecting and advancing a blank from the stack, an endless intermittently-movable secondary feeding mechanism for receiving the selected blank from said primary means and delivering it at such point, and a rotatable adhesive-applying means movable with the secondary means for spotting the blank with adhesive as it is being transported by said mechanism.

4. In mechanism for selecting, gumming and delivering blanks individually and successively from a stack of blanks to a predetermined point, primary feeding means for selecting and advancing a blank from the stack, an endless intermittently-movable secondary feeding mechanism for receiving the selected blank from said primary means and delivering it at such point, said mechanism including a succession of spaced apart gripping devices positionable to receive the selected blank from the primary means and discharge it at such point, and a rotatable adhesive-applying means movable in synchronism with said mechanism for applying adhesive to the selected blank.

5. In mechanism for selecting, gumming and delivering blanks individually and successively, means for selecting blanks singly from a stack of blanks and feeding them forward, a rotatable adhesive-applying

member for applying adhesive to a face of a selected blank, means for applying adhesive to a surface of said rotatable member, a rotatable presser arranged opposite the adhesive-applying member for pressing the blank thereagainst, and a secondary blank feeding means for transporting the adhesive-coated blank, said secondary means comprising an endless carrier having a plurality of spaced grippers for transporting a succession of blanks.

6. In mechanism for selecting, gumming and transporting blanks individually and successively, and in combination, means for selecting blanks singly from a stack of blanks and for advancing them forward, a pair of spaced-apart endless carriers having between them a plurality of regularly-spaced transverse bars and cooperating grippers constructed to engage the forward edge of and successively advance blanks, rotary adhesive-applying means for applying adhesive to a face of the blanks presented thereto by the selecting and advancing means, said adhesive-applying means comprising two cooperating rotary elements one of which is constructed to apply adhesive to a face of the blanks and the other of which operates as a co-operative backing or pressing member.

7. In mechanism for selecting, gumming and transporting blanks individually and successively, and in combination, primary feeding means for selecting blanks singly from a stack of blanks and feeding them forward, secondary feeding means for bodily transporting the selected blanks, rotary means associated with the secondary feeding means for applying adhesive to a face of the blanks to be transported and including a rotatable presser member for pressing blanks against the rotary adhesive-applying means, said secondary feeding means including a pair of endless carriers having companion portions arranged to move in a right line, and a plurality of spaced gripper devices carried by and arranged between the pair of endless carriers for successively engaging and transporting the blanks.

8. In mechanism for selecting, gumming and transporting blanks individually and successively and in combination, a support for a stack of blanks, primary feeding means for selecting the blanks singly from the stacked blanks and feeding them forward, secondary feeding means for bodily transporting the selected blanks, and rotary adhesive-applying means for applying adhesive to a face of the blanks fed forward by the primary feeding means and including a rotatable presser member for pressing blanks against the adhesive applying means, said secondary feeding means including a pair of spaced-apart endless carriers having transverse bars and grippers associated there-

130

with for transporting the blanks, and independent means co-operating with the grippers for operating them to receive the blanks at one point and for releasing them at 5 another point.

9. In mechanism for selecting, gumming and transporting blanks individually and successively and in combination, primary means for selecting blanks singly from a

- 10 stack of blanks and for feeding them forward, secondary feeding means for bodily transporting the selected blanks, rotary adhesive-applying means co-operatively associated with the secondary feeding means
- 15 for applying adhesive material to a face of the blanks to be transported, said secondary feeding means including a pair of spaced-apart endless carriers, supports for the carriers arranged to cause a portion thereof
- 20 to move in a right line, spaced gripping devices mounted at different points between carriers for transporting the blanks, and means for actuating the gripping devices at proper intervals to successively take the
- 25 blanks delivered by the primary means and for releasing the blanks at a predetermined point in the path of movement of the endless carriers.

10. In mechanism for selecting, gumming and delivering blanks individually and successively from a stack of blanks to a predetermined point, primary feeding means for selecting and advancing a blank from the stack, secondary feeding means for receiving the selected blank and delivering it at such point, means for applying adhesive to the selected blank while en route to said point, said applying means normally operating in a predetermined cycle, and automatic 35 means operative to affect such cycle to prevent adhesive application in the absence of a blank to receive the adhesive.

11. In mechanism for selecting, gumming and delivering blanks individually and successively from a stack of blanks to a predetermined point, primary feeding means for selecting and advancing a blank from the stack, secondary feeding means for receiving the selected blank and delivering it at 45 such point, means for applying adhesive to the selected blank while en route to said point, and automatic means operative in the control of the applying means to determine the periods of adhesive applying activity, 50 said automatic means extending into and being movable with said primary feeding means.

12. In mechanism for selecting, gumming and delivering blanks individually and successively from a stack of blanks to a predetermined point, primary feeding means for selecting and advancing a blank from the stack, secondary feeding means for receiving the selected blank and delivering it at 55 such point, means for applying adhesive to

the selected blank while en route to said point, said applying means normally operating in a predetermined cycle, and automatic means adapted to vary such cycle to prevent adhesive-applying activity, said automatic means extending into said primary feeding means and being maintained inactive by the presence of a properly-positioned blank in the primary means and rendered active in the absence of such blank. 70

13. In mechanism for selecting, gumming and delivering blanks individually and successively from a stack of blanks to a predetermined point, primary feeding means for selecting and advancing a blank from the stack, secondary feeding means for receiving the selected blank and delivering it at such point, rotary means co-operatively associated with the secondary feeding means for applying adhesive to one face of the 80 blanks as they are fed, and automatic means rendered operative upon failure of a blank to be fed by said primary means for throwing the adhesive-applying means out of operation and for throwing the latter into operation upon delivery of the next blank by the primary feeding means. 85

14. In mechanism for selecting, gumming and delivering blanks individually and successively from a stack of blanks to a predetermined point, primary feeding means for selecting and advancing a blank from the stack, secondary feeding means for receiving the selected blank and delivering it at such point, said secondary means including spaced-apart intermittently-movable endless carriers, a plurality of gripping devices supported by said carriers in spaced relation, each of said devices comprising normally-closed jaws and resilient means for normally maintaining the jaws in closed relation, means for opening said jaws at the beginning and ending of the intermittent movement, and means for applying adhesive to a face of a blank while the latter is 100 en route to said point. 105

15. In mechanism for selecting, gumming and delivering blanks individually and successively from a stack of blanks to a predetermined point, spaced-apart intermittently 115 movable endless carriers, a plurality of gripping devices supported by said carriers in spaced relation, each of said devices comprising normally-closed jaws and resilient means for normally maintaining the jaws in closed relation, means for opening said jaws at the beginning and ending of the intermittent movement, means for delivering a blank to said open jaws at the beginning of such movement, and mechanism for applying adhesive to a face of the blank while 120 en route to such point. 125

16. In mechanism for selecting, gumming and transporting blanks individually and successively from a stack of blanks to a pre- 130

determined point, primary feeding means for selecting and advancing a blank from the stack, secondary feeding means and its operating mechanism for receiving the selected blank from the primary means and delivering it at such point, adhesive applying mechanism associated with said secondary feeding means, and mechanism for disconnecting said secondary means from said operating mechanism upon failure of said primary means to deliver a blank to the secondary means.

17. In mechanism for selecting, gumming and transporting blanks individually and successively from a stack of blanks to a predetermined point, primary feeding means for selecting and advancing a blank from the stack, secondary feeding means and its operating mechanism for receiving the selected blank from the primary means and delivering it at such point, adhesive applying mechanism associated with said secondary feeding means, and an electrically-controlled trip mechanism for disconnecting said secondary means from said operating mechanism upon failure of said primary means to deliver a blank to the secondary means.

18. In mechanism for selecting, gumming and transporting blanks individually and successively from a stack of blanks to a predetermined point, primary feeding means for selecting and advancing a blank from the stack, secondary feeding means for receiving the selected blank from the primary means and delivering it at such point, means including a clutch device for intermittently operating the secondary feeding means, adhesive-applying mechanism associated with said secondary feeding means, a normally inoperative trip device for disconnecting said clutch, said device being actuated by said primary means, and electrical means for rendering said trip device operative to disengage the clutch upon failure of the primary means to deliver a blank to the secondary means.

19. As a means for delivering wrappers individually from a supply stack to a predetermined point, a support for the stack of wrappers, a reciprocating feeding means for individual wrapper blanks, and a cooperating intermittently movable endless feeding means provided with elements for taking a blank from said reciprocating means and transporting it to such point.

20. As a means for delivering wrappers individually from a supply stack to a predetermined point, a support for the stack of wrappers, means for picking a wrapper blank from such stack and for advancing the same substantially flatwise, and an endless intermittently movable secondary feeding means provided with elements operative to take the advanced blank from said pri-

mary feeding means and transport it to such point.

21. As a means for delivering wrappers individually from a supply stack to a predetermined point, a support for the stack of wrappers, reciprocating means for picking wrapper blanks successively from such stack and advancing the blanks individually, and a secondary feeding means operative to receive the advanced blank from the primary feeding means, said secondary means comprising an intermittently movable endless carrier, spaced normally closed gripping devices mounted on said carrier for receiving the advanced blanks and transporting them individually, means for temporarily opening the devices to receive the blanks from the reciprocating means, and other means for opening said devices to release the blanks from the devices at such point. 85

22. In means for transporting wrapper blanks individually while maintaining the blank flatwise, two spaced apart intermittently movable endless belts, a plurality of gripping devices supported by said belts in spaced relation, each of said devices comprising normally closed jaws and resilient means for normally maintaining the jaws in closed relation, and means for opening said jaws at the beginning and ending of the intermittent movement, and means for delivering a blank flatwise to said open jaws at the beginning of such movement. 95

23. In mechanism for selecting, gumming and delivering blanks individually and successively from a stack of blanks to a predetermined point, reciprocating primary feeding means for selecting and advancing a blank from a stack of blanks, an endless intermittently movable secondary feeding mechanism for receiving the selected blank from said primary means and delivering it at such point, and a rotatable adhesive applying means movable with the secondary feeding means for spotting the blank with adhesive as it is being transported by said mechanism. 100 105 110

24. In mechanism for selecting, gumming and delivering blanks individually and successively from a stack of blanks to a predetermined point, primary feeding means for selecting and advancing a blank from a stack of blanks, secondary feeding means for receiving the selected blank and delivering it at such point, said secondary means comprising spaced apart endless belts, gripping devices thereon, a shaft, and wheels carried by the shaft for driving said belts, radial arms fixed on and rotatable with said shaft, the outer ends of said arms carrying pads for applying spots of adhesive to the blank, and means for supplying a liquid adhesive to said pads. 115 120 125

25. In mechanism for selecting, gumming and delivering blanks individually and suc- 130

- cessively from a stack of blanks to a predetermined point, primary feeding means for selecting and advancing a blank from a stack of blanks, secondary feeding means 5 for receiving the selected blank and delivering it at such point, and means for applying an adhesive in spots to the upper face of the blank while the blank movements are controlled by the secondary means.
- 10 26. In mechanism for selecting, gumming and delivering blanks individually and successively from a stack of blanks to a predetermined point, primary feeding means for selecting and advancing a blank from a stack of blanks, secondary feeding means 15 for receiving the selected blank and delivering it at such point, rotary means cooperatively associated with said secondary feeding means for applying adhesive to one face 20 of the wrappers as they are fed, and automatic means rendered operative upon failure of a sheet to be fed by said primary feeding means for throwing the adhesive-applying means out of operation and for 25 throwing the latter into operation upon delivery of the next blank by the primary feeding means.
27. In mechanism for delivering blanks individually and successively from a stack 30 of blanks to a predetermined point, reciprocating primary feeding means for selecting and advancing a blank from the stack, secondary feeding means and its operating mechanism for receiving the selected blank 35 from the primary means and delivering it at such point, and mechanism for disconnecting said secondary means from its operating mechanism upon failure of said primary means to deliver a blank to the secondary 40 means.
28. In mechanism for delivering blanks individually and successively from a stack of blanks to a predetermined point, a reciprocating primary feeding means for selecting 45 and advancing a blank from the stack, secondary feeding means and its operating mechanism for receiving the selected blank from the primary means and delivering it at such point, and an electrically controlled 50 trip mechanism for disconnecting said secondary means from its operating mechanism upon failure of said primary means to deliver a blank to the secondary means.
29. In mechanism for delivering blanks 55 individually and successively from a stack of blanks to a predetermined point, reciprocating primary feeding means for selecting and advancing a blank from the stack, secondary feeding means for receiving the 60 selected blank from the primary means and delivering it at such point, means including a clutch device for intermittently operating the secondary feeding means, a normally inoperative trip device for disconnecting said clutch, said device being actuated by said 65 primary means, and electrical means for rendering said trip device operative to disengage the clutch upon failure of the primary means to deliver a blank to the secondary means.
30. In mechanism for delivering blanks 70 individually and successively from a stack of blanks to a predetermined point, primary feeding means, secondary feeding means, means including a clutch for intermittently 75 operating the secondary means, a normally inoperative trip device for disconnecting the clutch to stop or prevent the operation of the secondary means, said device being actuated by the primary means, an electromagnet for 80 rendering the trip device active, and electrical contacts carried by the primary means and in circuit with said magnet, said contacts being normally held inactive in the presence of a blank therebetween and 85 adapted to automatically complete the magnet energization in the absence of such blank.
31. In mechanism for delivering blanks 90 individually and successively from a stack of blanks to a predetermined point, reciprocating primary feeding means for selecting and advancing a blank from the stack, secondary feeding means for receiving the selected blank from the primary means for delivering it at such point, and mechanism 95 for disconnecting said secondary feeding means whenever the primary feeding means fails to deliver a wrapper to said secondary feeding means.
32. In mechanism for delivering blanks 100 individually and successively from a stack of blanks to a predetermined point, reciprocating primary feeding means for selecting and advancing a blank from the stack, secondary feeding means for receiving the 105 selected blank from the primary means for delivering it at such point, and an electrically operated trip mechanism for disconnecting said secondary feeding means whenever the primary feeding means fails to deliver a wrapper to said secondary feeding means.
33. In a machine of the class described, in combination, an endless carrier comprising a pair of endless chains, wheels supporting said chains, gripping devices mounted between said chains for engaging a wrapper and advancing the same with said chains and means for intermittently advancing said 115 endless carrier, and an arm rotatably mounted on the axis of said wheels and moving with said wheels, said arm having a pad adapted to engage the face of the wrapper being advanced by said conveyer to apply adhesive thereto.
34. In a machine of the class described, in combination, an endless carrier comprising a pair of endless chains, wheels sup-

porting said chains, gripping devices mounted between said chains for engaging a wrapper and advancing the same with said chains, means for intermittently advancing said 5 endless carrier and an arm rotatably mounted on the axis of said wheels and moving with said wheels, said arm having a pad adapted to engage the face of the wrapper being advanced by said conveyer to apply 10 an adhesive thereto and means for engaging the side of the wrapper opposite the pad simultaneously to facilitate the application of adhesive to the wrapper.

35. In a machine of the class described, 15 in combination, an endless carrier comprising endless chains, gripping devices carried between said chains for engaging the edge of a wrapper and advancing the same when said carrier is advanced, wheels about 20 which said chains pass, an arm mounted on the axis of said wheels and rotating in the same direction therewith, a pad carried by said arm for engaging the face of the wrapper and a rotating arm disposed and opposite to said first arm and having a path 25 adapted to engage the opposite side of the sheet simultaneously with said first pad to facilitate the application of adhesive to the wrapper.

30 36. In a machine for selecting, gumming and delivering wrapper blanks, in combination, spaced supports, an endless carrier having a portion arranged to move past said supports, engaging devices spaced 35 equally distant on the carrier for engaging each wrapper near its forward edge to draw the same forward, means for intermittently actuating said carrier always in the same direction to advance the forward edge of 40 the wrappers in succession past the said supports to bring each wrapper into position over said supports, said supports receiving the wrappers from the carrier and defining a folding well adapted to receive a package 45 fed into contact with the wrapper blanks received and supported thereby.

37. In a machine for selecting, gumming and delivering wrapper blanks, in combination, spaced supports, an endless carrier 50 arranged to move only in one direction having a portion arranged to move past said supports and having engaging devices for engaging each wrapper near its forward edge to draw the wrapper forward, means 55 for intermittently advancing said carrier to draw the forward edge of the wrappers successively past the said supports, means for releasing the said wrapper engaging devices when the wrapper is over said supports, the 60 said supports receiving the released wrappers, the supports defining a folding well adapted to receive a package fed into contact with the wrapper blanks supportingly received thereby.

38. In a machine for selecting, gumming 65 and delivering wrapper blanks, in combination, spaced resilient supports, an endless carrier having a portion arranged to move past said supports, engaging devices spaced on the carrier for engaging each wrapper 70 near its forward edge to draw the same forward, means for intermittently actuating said carrier always in the same direction to advance the forward edge of the wrappers in succession past the said supports to bring 75 each wrapper into position over said supports, the said supports being adapted to receive and resiliently hold the wrapper in position, the supports defining a folding well therebetween adapted to receive a package 80 fed into contact with the wrapper, the parts being so constructed that the supports resiliently resist wrapper withdrawal by the package fed into contact therewith.

39. In a machine for selecting, gumming 85 and delivering wrapper blanks, in combination, pneumatically controlled spaced supports, an endless carrier having a portion arranged to move past said supports, engaging devices spaced on the carrier for engaging each wrapper near its forward edge 90 to draw the same forward, means for intermittently actuating said carrier always in the same direction to advance the forward edge of the wrappers in succession past the said supports to bring each wrapper into 95 position over said supports, the said supports being adapted to receive and pneumatically hold the wrapper ends in position on the supports; the supports defining a folding well therebetween adapted to receive a package 100 fed into contact with the wrapper, the parts being so constructed that the supports resiliently resist wrapper withdrawal by the package fed into contact therewith.

40. In a machine for selecting, gumming and delivering wrapper blanks, in combination, spaced supports, an endless carrier having a portion arranged to move past said 110 supports, means on the carrier for engaging a wrapper near its forward edge for advancing and positioning the same over the said supports; the said supports receiving the wrappers from the carrier and defining a folding well adapted to receive the package 115 fed into contact with the wrapper blank supported thereby, the said supports being so constructed as to resiliently hold the wrapper ends, resisting wrapper withdrawal 120 activity by the package.

41. In a machine for selecting, gumming and delivering wrapper blanks, in combination, spaced supports for receiving the wrapper blank and holding the same over a folding channel, means for feeding the wrapper to said folding channel including two movable endless belts disposed on opposite sides 125

of said folding channel and a plurality of gripping devices supported by said belts in spaced relation, each of the said gripping devices comprising normally closed jaws,

5 means for intermittently actuating said belts to advance one of the said gripping devices beyond the spaced supports, resilient means tending to hold said jaws in closed position and means for controlling said jaws to open 10 to release the wrapper on the spaced supports.

42. In a machine for selecting, gumming and delivering wrapper blanks, spaced supports, an endless carrier, gripping means 15 carried thereby for engaging a wrapper near its forward edge, means for intermittently advancing said endless carrier to draw the wrapper in position over the said supports, means for releasing the said gripping device 20 when the wrapper is over said supports, means for yieldingly holding the wrapper in position on said supports, said supports defining a folding well adapted to receive a package forced against the wrapper and 25 down between the supports, the means for yieldingly holding the wrapper resisting wrapper withdrawal by the package fed into contact therewith.

43. In a machine for selecting, gumming and delivering wrapper blanks, in combination, pneumatically controlled spaced supports, an endless carrier having a portion arranged to move past said supports, means 30 on the carrier for engaging the wrapper near its forward edge for advancing the position of the same over said supports receiving the wrapper, and the said supports being adapted to pneumatically hold the same 35 in position, the supports defining a folding well therebetween adapted to receive a package fed into contact with the wrapper held thereby; the parts being so constructed that the supports resiliently resist wrapper withdrawal activity when the package is moved 40 in contact therewith.

44. In mechanism for selecting, gumming and delivering wrapper blanks individually and successively from a stack of blanks to a folding well, spaced supports, primary feeding means for selecting and advancing the blank from the stack, secondary feeding means for receiving the selected blank and delivering it to said spaced supports, the secondary feeding means including an intermittently movable endless carrier and spaced normally closed gripping devices mounted thereon and adapted to be opened 50 to receive the wrapper and to discharge the

same on the spaced supports and means for applying adhesive to the blank while en route to said supports.

45. As a means for delivering wrappers individually from a supply stack to a folding well, spaced supports at said folding well, a magazine for the stack of wrappers, 65 a reciprocating feeding means for individual wrapper blanks and a cooperative intermittently movable endless feeding means for receiving a blank from said reciprocating means and transporting to and depositing it on said spaced supports.

46. As a means for delivering wrappers individually from a supply stack to a folding well, spaced pneumatically controlled supports at the said folding well, a magazine for the stack of wrappers, a reciprocating feeding means for individual wrapper blanks and a cooperative intermittently movable endless feeding means for receiving a blank from said reciprocating means 80 and transporting it to and depositing it on the said spaced supports.

47. In a machine for selecting, gumming and delivering wrapper blanks, spaced supports for receiving the said blanks, a magazine for holding a stack of said blanks, primary feeding means for selecting and feeding a blank, secondary feeding means cooperating therewith for removing the said blank from the first feeding means and 90 transporting the same to the spaced supports, the said spaced supports receiving the blank from the secondary feeding means and being constructed and arranged to resiliently hold wrapper ends to resist wrapper 95 withdrawal.

48. In a machine for selecting, gumming and delivering wrapper blanks, spaced supports for receiving the said blanks, a magazine for holding a stack of said blanks, primary feeding means for selecting and feeding a blank, secondary feeding means cooperating therewith for removing the said blank from the first feeding means and transporting the same to the spaced supports, the said spaced supports receiving the blank from the secondary feeding means and being constructed and arranged to resiliently hold wrapper ends to resist wrapper 100 withdrawal, the said supports being provided with opposed resiliently mounted 105 rollers.

In testimony whereof we have hereunto set our hands.

JAMES D. REIFSNYDER.
GEORGE H. FATH.
